Patented June 15, 1920.

FIG. 1

FIG. 2

INVENTOR
M. DETTMAN

BY *J. M. Wright*

ATTY.

UNITED STATES PATENT OFFICE.

MAX DETTMAN, OF SAN FRANCISCO, CALIFORNIA.

MATCH-BOX HOLDER.

1,343,354.

Specification of Letters Patent. Patented June 15, 1920.

Application filed August 14, 1919. Serial No. 317,431.

To all whom it may concern:

Be it known that I, MAX DETTMAN, a citizen of the United States, residing at San Francisco, in the county of San Francisco and State of California, have invented 5 new and useful Improvements in Match-Box Holders, of which the following is a specification.

The object of the present invention is to 10 provide a device for supporting a match box so that the matches therein will always be in a convenient position for removal from the box, one or more at a time, until the box is empty.

15 In the accompanying drawing, Figure 1 is a perspective view of my improved match box holder; Fig. 2 is a vertical sectional view of the holder containing a match box.

20 On referring to the drawing, it will be seen that my improved holder is in two parts, both of which may be made of sheet metal having any desired finish, either tinned, enameled, nickel-plated, or otherwise finished. One part 1, holds a match box, 25 shown at 2, and the other part 3 is a tray adapted to receive burnt matches. The match box holder 1, which may be of any size to conform to the sizes of match boxes of various manufacturers, comprises a back 30 4 which extends both above and below the holder proper, as shown at 5, 6, which extensions have holes 7 therethrough adapting it to be attached to a wall or other object having a vertical surface. It has vertical 35 closed sides 8 and a front, which is open for the greater part of its length, but is closed at the top by a transverse strip 9 and the bottom by a transverse strip 11, both of said strips being integral with the sides.

40 At the bottom, the match box holder is closed in the front portion of the bottom by a strip 12 bent inwardly from the strip 11, but is open, as shown at 13, at the rear portion of the bottom. The sides 8 are extended below the match box holder, as 45 shown at 14, and are bent inward at their lower ends, as shown at 16, to form a guide-way for the tray 3. The top of the match box holder is open and the match box 2 box holder is inserted in the match box holder through 50 the open top, said open top being afterward closed by a closure 17, having two roof-like portions, sloping from the middle, and curved around at their lower edges to form guides 18 to engage flanges 19 extending from the tops of the sides 8 of the match

box holder. The closure 17, although used in the preferred form of my invention, is not an essential part thereof. At their front edges, said sides 8 are bent inward 60 for the greater part of their height, as shown at 21, to engage the curled over edge of the front side 22 of the match box severed from the remainder of the match box to within about one half inch from the bottom of the match box. The upper portions of the front edges of the sides 8 are bent outwardly upon oblique lines extending upwardly from the flanges 21 to the lower ends of the front strip 9, as shown 70 at 23, and the lower edge is also bent outwardly, as shown at 24, to facilitate the insertion of the hand in the match box to take matches therefrom.

The closure 17 is provided with roughened 75 portions 26 to facilitate striking of the matches.

A series of small patches 27 of phosphorescent paint is provided near the upper edge 80 of the back 4.

The mode of use of my match box holder will be understood from the foregoing description. The front side of the match box having been nearly severed from the remainder by cutting it therefrom along the 85 lines of juncture of said side with the body of the match box, the cover 17 is withdrawn and the match box is inserted through the open top of the holder, and the closure is then replaced. The front side 90 of the match box is drawn down from the top to obtain access to the matches in the match box, and, when the level of the matches in the match box is sufficiently low, the top edge of the front side 22 is curled 95 over downwardly and forwardly and its ends are inserted behind the flanges 21 and are curled over still more from time to time as the level of the matches in the match box descends, to obtain easy access to the 100 matches therein. When all the matches have been exhausted in the box, the box is removed from the holder, and a fresh box inserted in the same manner.

105

I claim:—

1. The combination with a match box holder comprising side walls, a back wall, and a bottom wall, flanges on the front edges of the side walls and terminating short of the upper ends of said side walls, a match 110 box mounted within said walls, and having one side thereof directed downwardly

and forwardly behind and in engagement with said flanges to permit access to the matches in said box.

2. In combination with a match box holder comprising side walls, a back wall and a bottom wall, of a match box mounted within the holder, said side walls extending

forwardly of the front plane of the match box, and flanges on said side walls extending at right angles thereto and providing 10 a space in which the front side of the match box may be rolled down behind and in engagement with said flanges.

MAX DETTMAN.
